Peter Fink, Chicago, Ill., assignor to Lucien Lelong, Inc., Chicago, Ill., a corporation of Illinois

Application February 14, 1950, Serial No. 7,930

Term of patent 14 years

(Cl. D58—8)

To all whom it may concern:

Be it known that I, Peter Fink, a citizen of the United States, residing at Chicago, in the county of Cook and State of Illinois, have invented a new, original, and ornamental Design for a Decanter or Similar Article, of which the following is a specification, reference being had to the accompanying drawing, forming a part thereof.

Figure 1 is a perspective view of a decanter or similar article, embodying my new design;

I claim:
The ornamental design for a decanter or similar article, as shown.

PETER FINK.
